UNITED STATES PATENT OFFICE

ALFRED CHMIELOWSKI, OF VIENNA, AUSTRIA, ASSIGNOR, BY DIRECT AND MESNE ASSIGNMENTS, TO SIGMUND KATSCHER, OF VIENNA, AUSTRIA

PROCESS OF DIRECTLY PRODUCING PHONOGRAPH CARRIERS SUITABLE TO BE PLAYED OFF

No Drawing. Application filed July 5, 1928, Serial No. 290,685, and in Austria May 23, 1927.

This invention relates to a process of directly producing phonogram bases or carriers suitable to be played off.

The present invention has for its object to produce with the known talking machines, adapted for plate-shaped, cylindrical or band-shaped sound records, all audible sound waves, such as for instance words, music, singing and so forth, and to immediately reproduce the said sound waves as often as desired.

According to the present invention a plate, cylinder or band consisting of gelatine is used as the carrier or base of the sound curves and the latter are engraved into the surface of the said carrier after the gelatine, preferably at its surface, has been covered with grease or a fatty substance in order to preserve the keenness of the producing needle.

The common sound boxes and guide mechanisms are used when providing the carrier with sound curves.

After the production is finished the gelatine provided with sound curves is hardened by means of an alcoholic formaldehyde solution, such as a mixture of one part formaldehyde and two parts methyl alcohol, either at once or after some time, in order to increase its resistance against mechanical (reproducing needle), chemical or atmospheric influences.

In order to attain reproduction without extraneous noises, the sound groove now embedded in the surface of the carrier is covered with fat or grease, whereby the gelatine surfaces (sound curves) laid bare by the producing needle are rendered more smooth by the greasy coating, so that the reproducing needle is guided smoothly.

A single sound box can be used for producing and reproducing, in which event a producing needle (steel needle) and a reproducing needle (glass- or sapphire needle) respectively are inserted in the sound box.

By my improved process there can be produced also "talking films" with perfect synchronism if the sound curves are engraved at the border of the perforations into the gelatine of the kinematographic film.

The object of the present invention is to

produce an original which can be played a practically unlimited number of times, whereby the known complicated and expensive methods (moulds) are dispensed with and the original can be produced by everybody with the aid of a common talking machine.

Where in the claims I employ the term "phonogram record," the same is to be understood to include not only disk, cylindrical, and other types of sound records, but also a strip of gelatine, photographic or moving picture film having a sound groove cut at the margin thereof.

I claim—

1. A phonogram record comprising a hardened gelatine layer having a sound groove cut therein.

2. A phonogram record comprising a surface layer of gelatine having a sound groove cut therein.

In testimony whereof I affix my signature.

ALFRED CHMIELOWSKI.
